(57) CLAIM

The ornamental design for an infant garment with attachable bib as shown and described.

DESCRIPTION

FIG. 1 is a perspective view of an infant garment with attachable bib showing my new design;

FIG. 2 is a front view thereof;

FIG. 3 is a right side view thereof;

FIG. 4 is a back view thereof;

FIG. 5 is a left side view thereof;

FIG. 6 is a top view thereof;

FIG. 7 is a bottom view thereof; and,

FIG. 8 is a front view with bib detached.

The broken lines represent portions and seams on the infant garment that form no part of the claim.

1 Claim, 8 Drawing Sheets
